Urgel Beausejour

By his Atty *W. S. Sprague*

UNITED STATES PATENT OFFICE.

URGEL BEAUSEJOUR, OF EAST SAGINAW, MICHIGAN.

CAR-COUPING.

SPECIFICATION forming part of Letters Patent No. 313,977, dated March 17, 1885.

Application filed August 2, 1884. (No model.)

To all whom it may concern:

Be it known that I, URGEL BEAUSEJOUR, of East Saginaw, in the county of Saginaw and State of Michigan, have invented new and useful Improvements in Car-Couplings; and I do hereby declare that the following is a full, clear, and exact description thereof, reference being had to the accompanying drawing, which form a part of this specification.

This invention relates to certain new and useful improvements in car-couplings of that class which will couple automatically when two cars to which they are attached are driven together, and which can be uncoupled without the necessity of going between the cars for that purpose, and which can be set so that in shunting the cars will not couple together.

The invention consists in the peculiar construction, combination, and arrangement of parts, as more fully hereinafter described.

In the accompanying drawing, which forms a part of this specification, my invention is shown in perspective, taken in reverse, or, in other words, looking upward at the bottom of the car-frame, showing only one end of such car, it, however, being necessary to have a duplicate of the invention on both ends of the car.

A represents the bed timbers of a car, below or to which are secured the timbers B, between which the buffer-spring C operates, and through which passes the rod D, to the forward end of which is pivotally secured the latch or hook coupling-bar E, the front end of which is supported by one or more stirrups, F, all constructed and arranged in the ordinary manner.

A spring, G, is so arranged as to exert its force against the rear side of the latch, as shown.

A chain or cord, H, is secured at one end to the rear side of said coupling-bar and at the other to one end of the lever I, which is pivotally secured to the timbers of the bed-frame. To the opposite end of this lever is secured another chain, J, which is led around a guide-pulley, K, and its opposite end secured to the shaft L, which is suitably journaled laterally across the car, with its ends projecting beyond the sides thereof, and upon these ends are secured the crank or hand-wheels M, and also the ratchet-wheels N.

A pawl, O, is secured to each side of the car in such position as to allow them to be engaged with the ratchet-wheels when desired.

When it is desired to couple cars together, 55 the pawls are disengaged from the ratchets, when the spring, pressing against the side of the coupling-bar, will force such bar into line with the buffer-bar, inclosed within the buffer-spring. The coupling upon the end of the adjacent car being in the same position, if the cars are run together the coupling-bars will engage their respective latches, each with the other, and the springs bearing against the rear faces of each will hold them in their engagement. 65 To uncouple, the operator turns one of the hand-wheels, thereby winding up the chain and drawing back the free end of the coupling-bars. If it is desired to prevent coupling, as in shunting, when the parts are in the 70 position last described, the pawl is engaged with the ratchet-wheel by the operator, when shunting may be done without danger of coupling. As these pawls are overweighted at their lower ends, a slight turn of the shaft in 75 the right direction disengages the pawl and ratchet, and the pawl remains hanging in a vertical position.

To enable this device to be successfully employed upon cars of different heights, I make 80 the latch-head P longer vertically than the width of the bar proper, allowing such additional width to project vertically beyond the said bar. A stirrup-stop, R, is so located as to embrace the coupling-latch and limit its 85 movement under the action of the spring in the rear of said bar, or that of the shaft and its connections.

By the employment of a coupling, as described, there is no necessity of going between 90 the cars for the purpose of coupling or uncoupling, as the whole work is controlled from the sides of the car through the means set forth.

What I claim as my invention is—

1. In a car-coupling, the combination of the 95 latch-coupling E, pivoted to the rod D, the shaft L, journaled across the bed of the car, the lever I, pivoted to said bed, hand-wheels M and ratchet-wheels N, secured upon the projecting ends of said shaft, the chain J, connecting the shaft with one end of said lever, and the chain H, connecting the opposite end

of said lever with the coupling-latch E, substantially as and for the purpose specified.

2. The combination of the latch or coupling bar E, the shaft L, journaled across the bed of the car, hand-wheels M and ratchet-wheels N, secured to the projecting ends of said shaft, pawls O, pivoted to the car-body, the lever I, pivoted at the center of its length to the bed of the car, the chain H, connecting one end of

the lever to the end of the latch E, the chain J, connecting the opposite end of said lever with said shaft, and the spring G, arranged to bear on said latch, substantially as and for the purpose specified.

URGEL BEAUSEJOUR.
